UNITED STATES PATENT OFFICE.

GEORGE A. BURNHAM, OF CLIFTONDALE, MASSACHUSETTS, ASSIGNOR TO SEARS B. CONDIT, JR., OF BOSTON, MASSACHUSETTS.

ELECTRIC COMPENSATOR.

1,140,247.

Specification of Letters Patent. Patented May 18, 1915.

Application filed September 15, 1909. Serial No. 517,821.

To all whom it may concern:

Be it known that I, GEORGE A. BURNHAM, a citizen of the United States, residing at Clifftondale, in the county of Essex and 5 State of Massachusetts, have invented an Improvement in Electric Compensators, of which the following description, in connection with the accompanying drawings, is a specification, like letters on the drawings 10 representing like parts.

My invention has for its object the automatic compensation in a supply system whereby the voltage may be regulated at the bus-bars to compensate for drop of potential 15 under the varying conditions of service of a consumption circuit at another point.

In carrying out my invention I provide mechanism whose operation depends upon the variation in speed of motor-operated circuit 20 making and breaking apparatus to vary the field excitation of the supply generator and regulate the voltage over wide ranges of load in the consumption circuit with a minimum amount of mechanism and light 25 moving parts.

The constructional details of my invention and its advantages will be pointed out more at length in the following description with reference to the accompanying drawings.

Figure 1 is a diagrammatic view of my invention as applied to an alternating system of distribution. Fig. 2 is a similar view as applied to a direct current system. 35 Fig. 3 is a diagrammatic detail. Fig. 4 is a diagrammatic view of a further development or more complete embodiment of the invention, applied to two or more machines operating in parallel. Fig. 5 is a central 40 vertical transverse sectional view, partly broken away, of the rotary contact device. Fig. 6 is a fragmentary transverse vertical section through the slotted portion of the shaft 49 of Fig. 5.

Referring to Fig. 1, the feed wires 1, 2 are shown in connection with translating devices 3, the current being derived from an alternating generator whose armature is indicated at 4 and field magnet coil at 5, the latter being connected by wires 6, 7 to an exciter armature 8 and field coil 9. Connected across the wires 1, 2 is a potential transformer 10, and in one of the wires, as 2, is a current transformer 11 leading by 55 wires 12, 13, 14, 15 to a contact-making

voltmeter coil 16 whose core 17 controls the lever 18, pivoted at 19 and having its movable contact 20 in position to coöperate with a stationary contact 21, being counterbalanced by a spring 22. The windings of the 60 compound coil 16 are supplied by potential and current transformers in the main circuit, core 17 being responsive to both current and voltage. It will be understood that any suitable contact-making voltmeter may 65 be employed which is adapted for the work; that shown comprises two differentially acting coils, one 16 tending to hold contacts 21, 20 open against spring 22 at normal load, the companion coil exerting an opposing force tending to close the contacts on 70 predetermined increase of load. An adjustable resistance 23 connects by a wire 24 with the lever 18 at one end and by a wire 25 with the contact 21 at the other end, and thence by a wire 26 to a motor 27. The 75 energy for said motor may be derived from any suitable source, the circuit being shown in Fig. 1 as completed by a wire 28 from a transformer 29 whose primary is connected 80 across the feeder wires 1, 2, the secondary being connected at 30 with the lever 18 of the voltmeter. Thus it is evident that the speed of the motor 27 will vary with the 85 voltage of the circuit 1, 2 and may be set as required for a normal speed by adjustable resistance 23. The motor is provided with a bevel pinion 31 meshing with a gear 32 which operates the rotary contact portion 90 of my compensating mechanism, the device in general being indicated at 33, and shown in detail in Fig. 5. Wires 34, 35 lead from the contact device 33 respectively to the opposite ends of the adjustable rheostat 36 of the exciter, preferably being capable of being varied by hand. Instead of connecting the wire 34 from the end of the rheostat directly to the field coil 9 of the exciter, I 95 interpose in series with the coil 9 an automatic cutout device shown as comprising a solenoid 37, one end of whose winding 38 leads to the field coil, and the other 39 leads to the rheostat and wire 34. The core 40 of said solenoid 37 is normally held up by an adjustable spring 41 and carries at its opposite end a contact plate 42 on a spindle 43 checked in its movement by any suitable means, as by a dash-pot 44, said contact-plate closing the circuit at proper times 100 between contacts 45, 46, the former connect- 105 110

ed by wire 47 with one end of the rheostat, and the latter by a wire 48 with an intermediate tap of the rheostat. Thus when current passes through the rheostat 36 of a value such that its drop of potential across the wires 34, 35 would injure the contact device 33, this is prevented by short-circuiting a portion of the rheostat through the closing of the short-circuit 47, 48 at the contacts 45, 46. In Fig. 5 I have shown the rotary contact device in enlarged detail, where it will be seen that the gear 32 is fast on the lower end of a shaft 49 mounted at its lower end in a guide bearing 50, and at its upper end in a thrust ball-bearing 51 carried by a central standard 52 of a surrounding cylindrical shell 53. On the upper end of this shaft 49 is mounted an arm 54 held against rotation thereon by any suitable means, but free to move longitudinally against the resistance of a spring 56, adjusted by nuts 57. At its free end the arm 54 carries an electric contact 58 freely movable radially in a brush-holder 59, maintained normally under outward tendency by a spring 60 and connected by a flexible conductor 61 to any suitable rotary conducting portion, preferably to the arm 54. The holder 59 has an upwardly extending portion 62 preferably vertically adjustable by a slot and bolt connection 63 with relation to the arm 54. Connected with the rotary shaft 49 is a stop, herein shown as an anti-friction wheel 64 mounted in a slot 65 in the shaft 49 on which bears the curved shoe end 66 of a lever 67 pivoted at 68 on a boss 69 of the arm 54, said lever 67 having a depending portion 70 carrying an adjustable weight 71. Above the shell 53 is a complementary cylindrical shell 72 separated from the former by insulation 73 which extends diagonally of the axis of said two shells, which latter carry binding posts 74, 75. A pressed-glass cover 76 is mounted on the top of the upper shell and is removably retained by spring clips 77.

In Fig. 4 I have indicated a further feature of my invention when the same is used in connection with a plurality of generators, two being shown as sufficient to make said application understood. The leads 34, 35 from the compensator member 33, the same as already described, are connected respectively to regulator bus-bars 78, 79, across which are switches 80, 81, one for each machine. Inasmuch as the latter are the same and the wiring the same as already described, I have shown merely the rheostat of each machine, herein indicated at 82, 83, respectively, and corresponding to the rheostat 36 above, from which rheostat lead-wires 84, 85 and 86, 87 to the field and armature respectively of the generator. Thus the operator by throwing the switch 80 in, effects the same single arrangement shown in Figs. 1 and 2, and by throwing in also

the switch 81 he causes the two generators to be regulated simultaneously by the same compensating mechanism. Thus, it will be readily seen that my compensating mechanism is capable of use with a plurality of generators, and does not require a separate compensating apparatus for each generator. Preferably a condenser 88 is interposed across the leads from the compensator 33 to take care of any undue sparking that would otherwise occur.

In operation the motor 27 continuously rotates the shaft 49, and hence moves the contact 58 in continuous engagement with the shells of the member 53, its relative period of engagement with one and the other of said shells depending upon the vertical position of the contact 58. Said vertical position is governed by the speed of rotation of the shaft 49, which throws the weight 71 outwardly by centrifugal force to a greater or less extent according to said speed, and thereby through the action of the cam-like shoe end of the weight raises the arm 54 and with it the contact 58, or permits the same to fall more or less. It will be observed that this centrifugal action is dependent upon the speed of rotation of the shaft 49, and hence upon the speed of motor 27, and the latter varies according to the variations in voltage of the circuit whose variations are to be compensated. Whenever the load 3 is increased the compound coil 16 holds the contacts 20, 21 closed, thereby cutting out the resistance 23 and permitting the motor 27 to increase its speed. This increase of speed of the motor correspondingly increases the speed of rotation of the shaft 49, which throws out the centrifugal weight 71, and thereby raises the contact 58 so that as it rotates it maintains contact with the shell 72 longer than before, with the result that the rheostat 36 of the exciter circuit is short-circuited for a greater aggregate length of time than previously, which increases the exciter voltage, thereby raising the voltage of the generator 4, 5, which raises the voltage of the line 1, 2 to the extent necessary to counteract the drop due to increase of load. Thereupon the contacts 20, 21 open, with the result that the motor slows down, the centrifugal weight falls, restoring the rotary contact 58 to a lower position where the aggregate closure of the short-circuit around rheostat 36 is of shorter duration. Thus as the load 3 varies the speed of the motor and the position of brush vary simultaneously. The brush and all its connected parts are exceedingly light, so that their momentum does not appreciably influence the speed of the motor. The rotation of the brush prevents it from heating by exposure to air, and as it moves on the inside of the shell a hard, effective contact is maintained. The motor might be

used without resistance 23, but not so effectually. The resistance permits the speed to be set more definitely for a normal load, and moreover reduces the intensity of sparking 5 at the contacts 20, 21.

I will now explain the action of the automatic cutout coöperating with the rheostat 36. On heavy load the potential drop across rheostat 36 would create sparking at brush 10 58 which would soon put the regulating apparatus out of commission. When such a condition arises solenoid 37 pulls down its core and contacts 45, 46 are bridged short-circuiting a part of the rheostat and reducing 15 5 15 the potential drop at the brush, reducing the severity of sparking. An effect is also produced on the voltmeter contacts 20, 21. The coil 16 opens or closes the contacts at a variable rate of vibration accordingly 20 20 20 as the effect of the current coil is large or small relatively to the tension of the spring 22; when the cutout operates it reduces the field resistance and lowers the potential across the contacts of the intermittent 25 25 25 interrupter 33 thereby protecting the contacts from danger of burning.

In Fig. 2 I have shown the invention as applied to a direct current system. The line wires 1, 2 are connected directly to the direct 30 30 30 current generator 8, 9, the coils in the voltmeter being operated from wires 89, 90, and a shunt 91 and wires 92, 93 across the line as shown, a wire 94 connecting from the line wire 2 to the lever 18, and a wire 95 from 35 35 35 the line-wire 1 to the motor to complete the circuit of the latter.

In Fig. 3 I have indicated a battery 96 for operating the motor instead of the potential 40 40 40 transformer 29 of Fig. 1, it being understood that the motor may be supplied with energy from any suitable source.

In all cases the operation of the automatic compensating mechanism is substantially the same, going through the same cycle of 45 45 45 operations to establish automatic compensation for voltage drop and current in the circuit of the generator or systems being regulated, and whenever the current in the controlling rheostat 36 becomes so high as to 50 50 50 endanger the contacts the relay 37 operates to short-circuit a part of the rheostat. The spring 41 of said relay is so adjusted that when a predetermined current value passes through the field coil 9 and said relay, the 55 55 55 contact disk 42 is drawn down to short-circuit a part of the resistance. The dashpot 44 prevents momentary changes in the field circuit from causing an operation of the relay. The compensation is caused by a 60 60 60 combination of the vertical position of the contact 58 and the rotary speed of said contact. Both of these are positive and definite, and are mutually dependent, so that the vertical position is due to centrifugal action 65 65 65 under varying speed, and effects effective

regulation in the way described. The circuit which includes wires 34, 35, which is an auxiliary circuit with relation to the main circuit, is continuously interrupted by the compensator and thereby acts on the main 70 70 70 circuit through the generator by automatically governing the duration of interruptions in the auxiliary circuit to a predetermined extent as determined by the motor whose speed changes in response to the variations in the main circuit.

Having thus described my invention, what I claim as new and desire to secure by Letters-Patent is:—

1. An apparatus of the kind described including a main circuit, a field circuit, a field resistance, and automatic make and break means for varying the value of the field strength, containing means for varying the length of interruption, said last mentioned varying means being controlled by a speed changing device for simultaneously changing the speed of interruption and also governing said controlled varying means to change the length of interruption. 80 80 80

2. An apparatus of the kind described including a main circuit, a field circuit, a field resistance, automatic make and break means for varying the value of the field strength responsive to a variable speed actuator and containing means under the control of said variable speed actuator to vary the length of interruption, said variable speed actuator simultaneously changing the speed of interruption of said make and break means 95 95 95 and also governing said controlled varying means to vary the length of interruption. 100 100 100

3. An apparatus of the kind described, including a main circuit, a field circuit and automatic means for varying the value of the field strength including make and break mechanism, and a variable speed device responsive to variations in voltage in the main circuit for changing the proportion of the make and break. 105 105 105

4. In an apparatus of the kind described, including a main circuit, a field circuit, automatic make and break means for varying the value of the field current, and a variable speed operating device for operating said make and break means variable in response to variations in voltage in said main circuit, the relative duration of make and break being dependent upon the speed changes of said operating device. 115 115 115

5. An apparatus of the kind described including a main circuit, a generator, a field circuit for said generator, means for varying the value of the field strength in accordance with speed changes including a make and break device whose relative duration of make and break is dependent upon speed changes in said device, and operating means for the latter having a variable speed in response to variations of voltage in the main circuit. 125 125 125

6. In an apparatus of the kind described, a main circuit, a generator, a field circuit for said generator, an automatic means for varying the value of the field strength having two relatively movable make and break members, and centrifugal means whose speed is responsive to variations in voltage in said main circuit for automatically varying the relative duration of the make and break. 70
7. In an apparatus of the kind described, a main circuit, a generator, a field circuit for the generator, and automatic means for varying the value of the field current having two relatively movable make and break members, one of which is stationary and the other rotary relatively thereto and whose position for varying the relative duration of the make and break is due to changes in its speed, and means for automatically varying the speed of rotation of said rotary member in response to variation in voltage in said main circuit. 75
8. An apparatus of the kind described, including a field circuit, a resistance, and automatic means for varying the value of the field strength by said resistance, including a stationary cylindrical conductor member composed of a plurality of parts insulated from each other, a coöperating rotary contact whose position for governing the relative duration of the make and break is due to changes in the speed of rotation thereof, and means for driving said contact. 80
9. An apparatus of the kind described, including a field circuit, a resistance, and automatic means for varying the value of the field strength by said resistance, including a stationary cylindrical conductor composed of a plurality of parts insulated from each other, a coöperating rotary contact whose position with relation to the stationary member is dependent solely upon changes in the speed of rotation thereof, and means for driving said contact at a variable speed. 85
10. An apparatus of the kind described, including a generator, a field circuit, a resistance, and automatic means for varying the value of the field strength by said resistance, including a stationary cylindrical conducting member composed of a plurality of parts insulated from each other, and a coöperating rotary contact having two movements responsive to conditions of the generator, one movement being longitudinally of said cylindrical member and the other concentrically thereof. 90
11. An apparatus of the kind described, including a field circuit, a resistance, and automatic means for varying the value of the field strength by said resistance, including a stationary cylindrical conductor member composed of a plurality of parts insulated from each other, a coöperating rotary contact having provision for movement longitudinally of said cylindrical member and also concentrically thereof, and centrifugal means for governing the position of said contact in accordance with the speed of movement thereof. 95
12. In an apparatus of the kind described, a main circuit, a continuously interrupted auxiliary circuit which reacts on said main circuit to regulate the voltage thereof, means for continuously interrupting said auxiliary circuit including two relatively movable make and break members, one of which rotates with relation to the other, and means responsive to variations in said main circuit for automatically varying the speed of said rotation to the extent required to maintain the desired voltage in the main circuit. 100
13. In an apparatus of the kind described, a main circuit, a continuously interrupted auxiliary circuit which reacts on said main circuit, means for continuously interrupting said auxiliary circuit including two relatively movable make and break members, one of which rotates with relation to the other, means responsive to variations in the main circuit for automatically varying the speed of said rotation, and centrifugal means for varying the duration of the interruptions in said auxiliary circuit in addition to the variations of said duration caused by said variations in the speed of rotation. 105
14. In an apparatus of the kind described, a line circuit, a compensator apparatus for compensating changes of voltage in said line circuit, including two relatively movable make and break members, at least one of which is continuously moving, actuating means responsive to variations in voltage in the line circuit for moving at a variable speed said continuously moving member, and separate means governed by said actuating means for changing to a predetermined extent the duration of the periods of interruption in addition to such changes therein as are due to the change in the speed of said movement. 110
15. A main circuit, a generator, a field circuit therefor, a rheostat in the field circuit, short-circuiting means for the rheostat, an automatic make and break regulator for the field circuit, and automatic means responsive to changes of the field current for operating said short-circuiting means whenever the field current reaches a predetermined value. 115
16. A main circuit, a generator therefor, a field circuit, a rheostat controlling the field circuit, an automatic make and break regulator for varying field current, a relay responsive to predetermined electrical conditions of the field circuit, a normally open short-circuit around a portion of the rheostat, and contact means controlled by said relay for closing said short-circuit whenever the field current reaches a value suffi- 120
- 125

cient to produce injurious sparking at the regulator contacts.

17. A main circuit, automatic compensating means therefor including two make and break members, one of which is continuously moving and whose variations in relative position of make and break are due solely to changes in its speed of movement, operating means for moving the latter in response to changes in voltage in said main circuit, an operating circuit for said operating means including a make and break regulating device, and a resistance around the contacts of said make and break device.

18. The combination in a voltage regulator for dynamo-electric machines, of a generator, a field circuit thereof, rapid field circuit interrupting means normally liable to sparking, an auxiliary circuit controlling the field circuit, and spark reducing means in said auxiliary circuit comprising a hand-adjusted rheostat for the field circuit, and an automatic cutout operative only upon the occurrence of predetermined current in the field circuit adapted to lower the potential at the interrupting means.

19. The combination in a voltage regulator for dynamo-electric machines, of a generator, a field circuit thereof, rapid field circuit interrupting means, an auxiliary circuit controlling the field circuit, means in said auxiliary circuit for preventing destructive sparking at the interrupting means, and an automatic cutout responsive to predetermined electrical conditions of the field circuit for controlling the spark reducing means.

20. In combination, a main circuit, a generator, its field and regulating resistance, a rapidly operating make and break device for intermittently shunting said resistance, and an automatic switching means responsive to the field current for varying the value of the resistance and thereby reducing potential across the make and break device.

21. The combination with a main circuit, a generator and its field circuit, of a voltage regulator containing means producing rapid make and break pulsations in said field circuit and normally liable to sparking, a resistance in said field circuit, and automatic cutout means responsive to field current to cut out a portion of said resistance upon the occurrence of predetermined electrical conditions, said cutout having a tendency to respond in unison with the operation of the regulator, and retarding means for preventing the operation of the cutout, said retarding means being ineffective to prevent the operation of the cutout within predetermined current limits.

22. The combination with a main circuit, a generator and its field circuit including a rheostat, of a voltage regulator responsive to

variations of voltage in said main circuit for varying the value of the field current including make and break contacts for shunting the field rheostat, and automatic safety means responsive to the field current for preventing destructive arcing between said make and break contacts.

23. In an apparatus of the kind described, a main circuit, a generator, a rheostat in series with the field circuit of the generator, an automatic make and break means for varying the field strength in response to variations in the electrical conditions of said circuit, and an automatic cutout responsive to field current for cutting out a portion of the resistance.

24. In an apparatus of the kind described, a main circuit, a generator, a resistance in series with the field circuit of said generator, an automatic make and break compensating means for varying the field strength in response to variations in said circuit, and an automatic cutout for cutting out a portion of said resistance whenever the current in the field circuit reaches a predetermined value.

25. In an apparatus of the kind described, a main circuit, a generator, a field circuit, a rheostat in series in the field circuit, an automatic make and break means for varying the field strength in accordance with the variations in the main circuit, a normally open shunt circuit around a portion of said rheostat, a relay controlling said shunt, and contact means operated by said relay for closing said shunt upon the flow of a predetermined current in said field circuit to prevent injury to said make and break means.

26. In an apparatus of the kind described, a main circuit, a continuously interrupted auxiliary circuit, means whereby the auxiliary circuit reacts on the main circuit, means for continuously interrupting said auxiliary circuit, including two relatively movable make and break members one of which rotates with relation to the other, a rotary actuator, and means responsive to variations in said main circuit for automatically varying said rotation to the extent required to maintain the desired voltage in the main circuit.

27. In an apparatus of the kind described, the combination of a main circuit, a generator and its field circuit, a voltage regulator containing intermittent interrupting means of varying duration shunting a resistance in series with the field circuit, differentially acting current and voltage coils governing the interrupting means, and mechanism including an automatic cutout responsive to predetermined electrical conditions in said field circuit, for reducing sparking at the interrupting means.

28. In an apparatus of the kind described, a line circuit, automatic compensating means therefor including two make and break

- members, one of which is continuously moving, a driving motor for moving the latter, an energizing circuit for said motor an automatic regulating device in said energizing 5 circuit responsive to variations in said line circuit, and a shunt resistance around said regulating device for giving smooth changes of speed regulation to said motor by said regulating device.
- 10 29. A compensator device for variations in voltage in a line circuit, including a stationary vertical cylinder, a central rotary shaft within said cylinder, a contact carried by said shaft to engage the cylinder, said 15 cylinder being composed of a plurality of parts having adjacent wedge-shaped portions which terminate obliquely to the axis of the shaft alternately engaged by said contact as the shaft rotates, at least one of said 20 parts being a conductor, means for rotating said shaft, and means for varying the position of said contact lengthwise of the cylinder in response to variations of voltage in 25 said line circuit.
- 25 30. A compensator device for variations in voltage in a line circuit, including a stationary vertical cylinder, a central rotary shaft within said cylinder, a contact carried by said shaft to engage said cylinder, said 30 cylinder being composed of a plurality of parts having adjacent wedge-shaped portions which terminate obliquely to the axis of the shaft alternately engaged by said contact as the shaft rotates, at least one of 35 said parts being a conductor, and means for rotating said shaft responsive to variations in voltage in the line circuit.
31. A compensator device for variations in voltage in a line circuit, including a stationary vertical cylinder, a central rotary shaft within said cylinder, a contact carried by said shaft to engage said cylinder, said cylinder being composed of a plurality of parts having adjacent wedge-shaped portions which terminate obliquely to the axis of the shaft alternately engaged by said contact as the shaft rotates, at least one of said parts being a conductor, a motor for driving said shaft at a variable speed responsive to 45 variations in voltage in said line circuit, and means for shifting said contact transversely to the direction of its rotation in accordance with the variations in the speed of said rotation.
- 50 55. 32. A compensator device for variations in voltage in a line circuit, including a stationary vertical cylinder, a central rotary shaft within said cylinder, a contact carried by said shaft to engage said cylinder movable with said shaft and also longitudinally thereof, said cylinder being composed of a plurality of parts having adjacent wedge-shaped portions which terminate obliquely to the axis of the shaft alternately engaged by said contact as the shaft rotates, at least one of said parts being a conductor, means for rotating said shaft, and centrifugal means for moving said contact longitudinally of said shaft in accordance with the speed of the shaft.
33. A compensator device for variations in voltage in a line circuit, including a stationary vertical cylinder, a central rotary shaft within said cylinder, a contact carried by said shaft to engage said cylinder movable with said shaft and also longitudinally thereof, said cylinder being composed of a plurality of parts having adjacent wedge-shaped portions which terminate obliquely to the axis of the shaft, alternately engaged by said contact as the shaft rotates, at least one of said parts being a conductor, means for rotating said shaft, centrifugal means for moving said contact longitudinally of said shaft in accordance with the speed of the shaft, and adjusting means for varying the centrifugal effect.
34. The combination with a dynamo-electric machine, and a resistor in the field circuit thereof, of means for adjusting the effective value of the resistor, and means for separately adjusting the value of said resistor in accordance with variations of an electrical condition of the dynamo-electric machine.
35. The combination with a main circuit, a dynamo-electric machine associated therewith, and an exciter for the dynamo-electric machine, of a resistor in the exciter field circuit, means for establishing and interrupting a shunt circuit to said resistor in accordance with variations in the electrical condition of said main circuit, and means for separately adjusting the value of said resistor responsive to the electrical condition of a circuit of the exciter.
